UNITED STATES PATENT OFFICE

2,644,107

PREHEAT NEUTRALIZING CIRCUIT FOR
FLUORESCENT LAMPS

Raymond L. Keiffer, Chagrin Falls, and Eugene Lemmers, Cleveland Heights, Ohio, assignors to General Electric Company, a corporation of New York

Application November 23, 1949, Serial No. 129,158

5 Claims. (Cl. 315—95)

1

This invention relates generally to starting and operating circuits for electric discharge devices such as fluorescent lamps, and more particularly to a new and improved switchless circuit and transformer structure for preheating the filamentary electrodes of such lamps at starting, and for eliminating the heating current after the discharge has started within the lamps.

Circuits presently in commercial use for operating fluorescent lamps are generally provided, either with switching means to allow preheating of the lamp electrodes to an electron-emitting temperature, or with high voltage high leakage-reactance transformers to start the lamps directly without any preheating of the electrodes. The first method of operation necessitates an undesirable delay in starting the lamp after the initial application of voltage to the circuit, and often results in undesirable flickering when the lamp fails to start on the first attempt; the second method places considerable electrical stress on the lamp electrodes which, other factors being equal, results in a shorter lamp life.

In our copending United States application No. 731,488 (Lemmers and Keiffer), filed February 28, 1947, now U. S. Patent 2,504,549, assigned to the same assignee as the present invention, there is disclosed a circuit for impressing heating voltages across the filamentary electrodes of a fluorescent lamp at starting, which circuit comprises three windings per electrode for neutralizing these voltages through changes in phase and magnitude of currents through a transformer consequent upon conduction in the lamps.

The present invention utilizes basically the same principles as described in the aforementioned application, and is concerned with an improved and more economical circuit and transformer structure for electrode preheating and subsequent neutralization in a like manner, wherein the number of windings per electrode is substantially reduced.

Accordingly, it is an object of our invention to provide an improved and simplified circuit for switchless starting and operation of fluorescent lamps, which permits the application of heating voltages to the filamentary electrodes of such lamps previous to starting, and which, immediately upon initiation of a discharge within said lamps, discontinues said heating voltages by means of changes in the phases and magnitudes of their components so as to substantially neutralize them.

Another object of our invention is to provide

2

an improved circuit for effecting the first-mentioned object and which, in addition, is well adapted to extension to any number of lamps by the simple expedient of multiplying the windings on an auxiliary transformer.

A further object of our invention is to provide a circuit which, in addition to fulfilling the previously mentioned objects, is particularly adaptable to certain modifications for providing a starting voltage to an auxiliary electrode, which starting voltage is likewise neutralized after the lamps have started, in the same manner as the heating voltages.

For further objects and advantages and for a better understanding of our invention, attention is now directed to the following description and to the accompanying drawings. The novel features of our invention will be more clearly pointed out in the appended claims.

In the drawings:

Fig. 1 is a schematic diagram of a starting and operating circuit for a pair of fluorescent lamps embodying our invention.

Figs. 2 and 3 are vector diagrams for the purpose of illustrating the voltage relationships in the windings of the transformer of Fig. 1, under starting and operating conditions, respectively.

Fig. 4 is a schematic diagram of a modified form of our neutralizing circuit as applied to a low reactance transformer of well known design.

Fig. 5 is a diagrammatic representation of a transformer structure embodying certain features of my invention.

Referring to Fig. 1, there is shown a pair of electric discharge devices 1, 1' such as fluorescent lamps, which will be referred to henceforth as the lag lamp and the lead lamp, respectively. These lamps comprise elongated tubular or cylindrical envelopes 2, 2', which have sealed into their ends filamentary electrodes 3, 4, and 5, 6, respectively. These electrodes may be constituted by coils of tungsten wire activated with oxides of alkaline earth metals, such as barium and strontium oxides. The envelopes 2, 2' contain rare gases such as krypton, neon, argon, or mixtures thereof, at a pressure of a few millimeters, and a small quantity of mercury. The devices 1, 1' may be low pressure, positive column lamps of the fluorescent type, provided with a suitable phosphor coating. This fluorescent coating, upon excitation by the radiation produced by an electric discharge between the electrodes, transforms a short wave length radiation due to the discharge, into a longer wave length radiation occurring within the visible range.

The lamps 1, 1' are connected in a lagging power factor load circuit 7, 8 and a leading power factor load circuit 9, 8, respectively, which circuits are connected across a suitable source of potential. In the drawings, we have illustrated a voltage step-up autotransformer 10, comprising a primary winding 11 and a pair of secondary windings 12 and 13. The secondary windings are loosely coupled to the primary winding and have considerable leakage reactance; such a structure is relatively well known in the art, and permits utilization of the secondary windings both as voltage step-up windings, and as ballast reactances for limiting the discharge current through the lamps. The lag lamp is connected directly through conductor 7 to secondary winding 12, whereas the lead lamp is connected through its conductor 9 to winding 13, in series with a capacitor 14 which performs the usual function of inverting the total reactance in this part of the circuit from inductive to capacitive.

In accordance with the principles disclosed in our application No. 731,488, voltages for heating the filamentary electrodes of the lamps may be provided by means of three sources, these sources having predetermined phase relations which change upon the initiation of a discharge through the lamps. In the above-mentioned application, we have shown three tertiary windings, coupled to the three windings of autotransformer 12, for each of the four filamentary electrodes. In other words, three tertiary windings are required for each lamp electrode so that for the two lamps illustrated herein, four groups of three tertiary windings, that is, a total of twelve tertiary windings are required.

In accordance with our present invention, the number of tertiary windings is greatly reduced. Associated with each winding of autotransformer 10 is a single tertiary winding, these tertiary windings being 15, 16, and 17 for windings 11, 12, and 13, respectively. The three tertiary windings are connected in series across the primary winding 18 of an auxiliary transformer 19, which transformer will be referred to henceforth as the cathode heating transformer. Transformer 19 may be of conventional construction, and is provided with as many secondary windings as there are filamentary electrodes which it is desired to heat. As illustrated herein, transformer 19 is provided with secondary windings 20, 21, 22, and 23 for electrodes 3, 4, 5, and 6, respectively.

The turns of the tertiary windings in autotransformer 12 are so proportioned that a resultant voltage is impressed across primary 18 of cathode heating transformer 19 at starting of the lamps, and this voltage is substantially neutralized after a discharge has started in the lamps. It will be obvious to those skilled in the art that it is thereafter a relatively simple matter to design cathode heating transformer 19 to have the secondary windings thereof transform the applied voltage to any desired value of voltage for heating the lamp electrodes, or for performing other functions.

Referring to Figs. 2 and 3, the vector diagrams therein illustrate the phase and magnitudes of the voltages in the tertiary windings of autotransformer 12, Fig. 2 being applicable to the voltage existing before starting, and Fig. 3 being applicable to voltages existing during lamp operation.

When the supply voltage is initially applied 75

across primary winding 11 of autotransformer 10, the induced voltages in secondary windings 12 and 13 are practically in phase with the voltage existing across the primary winding, and there is no discharge current circulating through windings 12 and 13 to disturb these phase relationships. Accordingly, the voltages induced in tertiary windings 15, 16, and 17 are in like phase and may be represented by vectors V_{15} , V_{16} , and V_{17} , respectively. These voltages add up to produce the resultant V_r which has a magnitude, after conversion through the cathode heating transformer 19, sufficient to cause heating of the filamentary electrodes in the lamps.

After the lamps have attained an electron-emitting temperature, the arc or discharge strikes within them; and the phases of the currents through the secondary windings 12 and 13 are respectively retarded and advanced. This is due to the fact that the leakage reactance of winding 12 introduces an inductive reactance in series with lag lamp 1, whereas capacitor 14 introduces a capacitive reactance in series with lead lamp 1' which overcomes the leakage reactance of secondary winding 13. The phases of the voltages induced in tertiary windings 16 and 17 are retarded and advanced respectively in the same fashion as the currents through secondary windings 12 and 13, and the voltage induced in tertiary winding 15 naturally remains unchanged. Accordingly, the voltages in the tertiary windings may be represented by vectors V_{15}' , V_{16}' , and V_{17}' , of Fig. 3 and these now add up vectorially to produce a resultant V_r' of substantially diminished magnitude.

In practice, complete neutralization is difficult to obtain because of the potential drop in the filamentary electrodes of the lamp produced by the arc or discharge current; the resultant voltage V_r' , however, is small enough to be negligible. In fact, perfect correlation between the magnitudes and phases of the voltages in the tertiary windings to obtain substantially zero resultant voltage during lamp operation is not necessary for the successful operation of the circuit, and a small amount of residual electrode-heating current is often desirable in order to lower the cathode voltage or arc drop.

Referring once more to Fig. 1, there is shown, in cathode heating transformer 19, an auxiliary secondary winding 24, illustrated in dotted outline. This winding may be utilized, if desired, to provide a starting voltage to a pair of auxiliary electrodes 25, 25' in the lamps. These electrodes may be constituted by stripes of conductive metallic paint applied to the surfaces of envelopes 2 and 2' of lamps 1, 1', respectively. The uses and principles of operation of such auxiliary starting electrodes are well known in the art and need not be described except to state that they permit a lowering of the starting voltage required across the main electrodes. It will be apparent that by obtaining the auxiliary starting voltage from cathode heating transformer 19 in accordance with our invention, the starting voltage is removed from the stripes or auxiliary electrodes as soon as the discharge is started within the lamps. This is due to the fact that the starting voltage is neutralized in exactly the same fashion as the heating current to the filamentary electrodes. This is a noteworthy feature since it is generally advantageous to remove high voltages from circuits with which operating personnel may come into contact.

Although the circuit has thus far been de-

scribed with reference to a high leakage-reactance type of transformer, wherein the ballasting action required for limiting the discharge current through the lamps is provided by the secondary windings of the step-up transformer, the circuit is equally applicable to a low reactance type of step-up transformer. Such a circuit is illustrated in Fig. 4, wherein similar reference numerals refer to corresponding elements. Thus, referring to Fig. 4, step-up autotransformer 10 comprises, as before, a primary winding 11, but this winding is now continued into a tightly coupled section 11' which provides a voltage step-up action. Connected to the outer end of section 11' are separate ballasting reactances 12' and 13', reactance 12' being connected directly, and reactance 13' being connected through the usual phase advancing capacitor 14. The electrode heating and neutralizing windings 15, 16, and 17 are coupled to windings 11, 12', and 13', respectively, the remainder of the circuit being in all other respects similar to that of Fig. 1.

The operation of this circuit is likewise similar to that of Fig. 1. The voltage for heating the lamp electrodes at starting is generated in winding 15. After the discharges have started, the voltages induced in windings 16 and 17 by the discharge current flowing through ballast reactances 12' and 13' add vectorially to the voltage induced in winding 15 to produce a resultant of substantially zero magnitude, thereby neutralizing the electrode heating. Cathode heating transformer 19 provides the required transformation for applying the resultant of the induced voltages to the various lamp electrodes.

Fig. 4 is a diagrammatic representation of a transformer, similar to that described in application No. 690,855 of Charles W. Kronmiller, filed August 16, 1946, and assigned to the same assignee as the present invention. The transformer herein is adapted to provide the windings required by the circuit of Fig. 1, and similar reference numerals refer to corresponding circuit elements. Transformers 10 and 19 comprise a common core 26; the transformer structure built upon core 26 to the right of section line 27-27' constitutes transformer 10, while the structure to the left of the section line constitutes transformer 19. Primary winding 11 and secondary windings 12 and 13 are mounted in separate slots in core members 28 and 28'; and tertiary windings 15, 16, and 17 are likewise mounted in these slots in close coupling with their associated main windings. Air gaps 29, 30, and 31 provide the desired leakage reactance between main windings.

The windings 18, 20, 21, 22, 23, and 24 of transformer 19 are mounted in a slot in core members 32 and 32'. An air gap 33 provides the necessary magnetic decoupling between transformers 19 and 10. It is to be understood that this particular transformer structure is given simply by way of non-limitative illustration; and, obviously, separate transformer structures may be utilized if desired.

While certain specific embodiments have been shown and described, it will, of course, be understood that various modifications may be made without departing from the invention. Thus, it will be obvious that the circuit may be modified to include any number of lamps by providing two additional secondary windings for the electrodes of each additional lamp. Likewise, whereas we have shown particular circuits comprising a step-up autotransformer, it will be evident that other

circuits which produce like results may be used in lieu of the one which has been illustrated by adding tertiary windings to it in the manner described in our invention. The appended claims are, therefore, intended to cover any such modifications coming within the true spirit and scope of the invention.

What we claim as new and desire to secure by Letters Patent of the United States is:

1. Apparatus for starting and operating electric discharge devices of the type including a pair of thermionic electrodes, comprising: a primary inductance adapted for connection to an alternating current supply, and a pair of secondary inductances connected to said primary inductance for limiting the current supplied to a lagging and to a leading power factor load circuit each including one of said devices; three tertiary windings, separate ones of said tertiary windings being coupled to said primary and secondary inductances, said tertiary windings being connected in series and poled for producing a resultant voltage the magnitude of which varies with the current conducted by said secondary inductances, and auxiliary transforming means comprising a primary winding connected across said tertiary windings in series and also including a plurality of secondary windings adapted to be connected to the electrodes of said discharge devices for providing heating current thereto.

2. Apparatus for starting and operating electric discharge devices of the type including a pair of thermionic electrodes, comprising: a magnetic core structure having wound thereon a primary winding adapted for connection to an alternating current supply, and a pair of secondary windings inductively coupled to said primary winding with high leakage reactance in said core structure therebetween, and connected to said primary winding for limiting the current supplied to a lagging and to a leading power factor load circuit each including one of said devices; three tertiary windings, separate ones of said tertiary windings being coupled to said primary and secondary windings, said tertiary windings being connected in series and poled for producing a resultant voltage the magnitude of which varies in accordance with the current conducted by said secondary windings; and auxiliary transforming means comprising a primary winding connected across said tertiary windings in series, and a plurality of secondary windings adapted to be connected to the electrodes of said discharge devices for providing heating current thereto.

3. Apparatus for starting and operating electric discharge devices of the type including a pair of thermionic filamentary electrodes, comprising: a magnetic core structure having wound thereon a primary winding for connection to an alternating current supply, and a pair of secondary windings connected to said primary winding, and inductively coupled thereto with high leakage reactance in said core structure therebetween for limiting the current supplied to a lagging and to a leading power factor load circuit each including one of said devices; three tertiary windings, respective ones of said tertiary windings being inductively coupled to said primary winding and to said secondary windings, the tertiary winding coupled to said primary winding producing a reference voltage, and the tertiary windings coupled to said secondary windings producing components of voltage variable in magnitude and phase in response to currents conducted by said secondary windings, said tertiary windings being

connected in series and poled so that the resultant of said reference voltage and said components is reduced upon the flow of current through said secondary windings; and an auxiliary transformer comprising a primary winding connected across said tertiary windings in series for receiving said resultant voltage, and secondary windings coupled thereto for converting said resultant to voltages of desired amplitude adapted to be applied to the electrodes of said discharge devices for providing heating thereof at starting.

4. Apparatus for starting and operating electric discharge devices of the type including a pair of thermionic filamentary electrodes and an auxiliary starting electrode, comprising: a magnetic core structure having wound thereon a primary winding for connection to an alternating current supply, and a pair of secondary windings connected to said primary inductance, and coupled thereto with high leakage reactance in said core structure therebetween for limiting the current supplied to a lagging and to a leading power factor load circuit each including one of said devices; three tertiary windings, respective ones of said tertiary windings being inductively coupled to said primary winding and to said secondary windings, the tertiary winding coupled to said primary winding producing a reference voltage, and the tertiary windings coupled to said secondary windings producing components of voltage variable in magnitude and phase in response to the currents conducted by said secondary windings, said tertiary windings being connected in series and poled so that the resultant of said reference voltage and said components is reduced upon the flow of current through said secondary windings; and an auxiliary transformer comprising a primary winding connected across said tertiary windings in series for receiving said resultant voltage, secondary windings coupled thereto for converting said resultant to voltages of desired amplitude adapted to be supplied to the electrodes of discharge lamps for heating thereof at starting, and an auxiliary winding coupled thereto for converting said resultant to a voltage

10 of desired amplitude adapted to be applied to said starting electrodes.

5. A transformer structure comprising: a magnetic core, primary and secondary windings on said core, said windings being loosely coupled by means of a leakage flux path therebetween; connections linking said windings in autotransformer relation for providing a relatively high open circuit voltage and a relatively low operating voltage when load currents flow therethrough to associated leading and lagging circuits for operating discharge devices of the filamentary electrode type; three tertiary windings mounted on said core, separate ones of said windings being closely coupled respectively with said primary and secondary windings, said tertiary windings being connected in series and poled to produce a resultant voltage the magnitude of which decreases with the current conducted by said secondary windings; and auxiliary windings mounted on said core, said auxiliary windings being relatively decoupled from previously mentioned windings by means of high leakage flux paths, said auxiliary windings comprising an auxiliary primary winding connected across said tertiary windings in series for receiving a resultant voltage having a substantial value when no load current flows in said primary and secondary windings and having a lesser value when load currents flow therein, 20 and auxiliary secondary windings closely coupled to said auxiliary primary winding for converting said resultant voltage to voltages of predetermined amplitude for application to the electrodes of said devices to provide heating thereof.
